UNITED STATES PATENT OFFICE

Patent No. 1,985,646, issued December 25, 1934, to Carl Sjögren, Wessington Springs, S. Dak., for a metallic clip forming machine, Serial No. 701,697, filed December 9, 1933.

METALLIC CLIP FORMING MACHINE

Charl Sjögren, Wessington Springs, S. Dak.

Application December 9, 1933, Serial No. 701,697

2 Claims. (Cl. 153—34)

This invention relates to a machine designed for making clips employed in securing articles such as tubes of tooth paste, solder, or the like to display cards.

5 The primary object of the invention is to provide a machine of this character wherein strips of sheet metal material may be fed into the machine, where the strips are bent into shape by the action of the dies of the machine, forcing the metal against an anvil, also forming a part of the machine.

Another object of the invention is to provide means for receiving the metal strips and guiding the metal strips to the anvil or former, in such 15 a way that the strips of metal will be held in position against the anvil, and will be accurately formed into clips, when the dies are brought into operation.

A still further object of the invention is the 20 provision of means for directing the clips, formed by the machine, into a container supported over the frame of the machine, where the clips may be readily removed.

With the foregoing and other objects in view, 25 which will appear as the description proceeds, the invention resides in the combination and arrangement of parts and in the details of construction hereinafter described and claimed, it being understood that changes in the precise embodiment of the invention herein disclosed, 30 may be made without departing from the spirit of the invention.

Referring to the drawings:

Figure 1 is an elevational view of a machine 35 constructed in accordance with the invention, the table of the machine being shown in section.

Figure 2 is a front elevational view of the machine.

40 Figure 3 is a plan view of the machine.

Figure 4 is a sectional view taken directly under the table of the machine.

Figure 5 is an enlarged detail view illustrating 45 the action of the dies with respect to the anvil, in the forming of clips.

Figure 6 is a perspective view of one of the clips.

Referring to the drawings in detail, the machine embodies a frame including supporting posts 5, that are held in spaced relation with each other by means of the straps 6, that are connected with the supporting posts, as clearly shown by the drawings.

The table of the machine is indicated by the 55 reference character 7, and is provided with a

slot 8 and transverse slots 9, the slot 8 accommodating the toothed end of the bell-crank lever 10, while the slots 9, accommodate the toothed ends of the bell-crank levers 12.

Disposed directly under the top 7, and arranged on opposite sides of the slot 8, are angle bars 13 that have their depending flanges 14 arranged in spaced relation with each other, where they are formed with openings to receive the pivot pin 15,

on which the bell-crank lever 10 is pivotally mounted.

Angle bars 16 are also disposed under the table 7 and are arranged transversely with respect to the angle bars 13, the angle bars 16 having their flanges 17 arranged in spaced relation with each other and formed with openings to accommodate the pivot pins 18, on which the bell-crank levers 12 are pivotally mounted.

Secured directly above the angle bars 13 and 16, and arranged on the upper surface of the table 20 7, are spaced bars 19, the spaces between the bars 19 providing guideways for the dies 20, 21 and 22 respectively. Cover plates 23 close the guideways and secure the dies against displacement.

These cover plates 23 are secured in position by means of the screws 24, so that they may be readily and easily removed and replaced.

As clearly shown by the drawings, the die 20 is formed with openings to receive the teeth of the bell-crank lever 10, so that when the bell-crank lever 10 is moved, the die 20 will be operated or slid within its guideway, to accomplish the purpose of the invention.

The dies 21 and 22 are also formed with openings to accommodate the teeth of the bell-crank levers 12, so that movement of the bell-crank levers 12 will be transmitted to the dies 21 and 22, as the bell-crank levers are operated.

The cover plate 23 that extends transversely of the table, is formed with a cut out portion of a length to accommodate the spring fingers 25, that are formed at one end of the cover plate 23, disposed transversely with respect to the first mentioned cover plate, the spring fingers providing a guide into which the blanks, used in the forma-

tion of the clips, are fed.

The reference character 26 designates a bolt that is formed with a threaded extremity extended through the transverse cover plate 23 where it is provided with a nut 27, securing the bolt in position.

A circular enlargement indicated at 28 is formed on the bolt 26, and is disposed directly under the cover plate at a point adjacent to the spring fingers or guide 25, so that a blank placed in the

guide will fall to a position directly in front of the circular enlargement which constitutes the anvil of the machine.

The die 21 has its inner end curved to conform 5 to the shape of the anvil, and the dies 21 and 22 have curved cut out portions also conforming to the curvature of the die, so that when the die 21 is moved into engagement with the blank, which in the present showing is indicated at A, one side 10 of the clip will be formed, and when the curved portions of the dies 21 and 22 are brought into engagement with the blank A, the formation of the clip will be completed. As the dies move rearwardly or away from the clip, the clip being constructed of sheet metal material, will open slightly, disengaging the anvil. The clip will now fall 15 into the chute 29, which is supported directly under the anvil. The chute has its discharge ends disposed within the container 30, which is supported by the frame of the machine, to receive 20 clips, from where they may be removed for use.

Pivoted mounted on the frame, is a treadle 31 that is engaged by the foot of the operator and pressed downwardly, when the die 20 is to be moved towards the anvil. This treadle 31 is connected to the bell-crank lever 10 by means of the rod 32, so that movement of the treadle will be transmitted to the bell-crank lever to accomplish the movement described. In order that the bell-crank lever 10 will be immediately returned to its initial position, coiled springs 33 and 34 are provided, the spring 33 having connection with the bell-crank lever at one of its ends, while the opposite end thereof is anchored to one 35 of the supporting posts or the legs of the frame.

The spring 34 has its upper end anchored to the frame at 35, while the opposite end thereof is connected to the rod 36, that is connected to the treadle 31.

40 The reference character 37 designates the treadle that operates the bell-crank levers 12, the treadle 37 being connected to the bell-crank levers 12 by means of the connecting rods 38.

These rods 32 and 38 extend through the 45 treadles with which they are connected, and are supplied with coiled springs 39, that cushion the action of the treadles on their downward movement.

40 The bell crank levers 12 are returned to their active positions by means of the coiled springs

40, that are shown as connected therewith, the opposite ends of the springs 40 being anchored to the posts or legs of the frame of the machine.

Connected with the treadle 37 is a rod 41 that connects with the plate 42, in which the coiled springs 43 are connected, the coiled springs 43 being anchored to the plate 44, secured to the underside of the table 7.

From the foregoing it will be obvious that due to the construction shown and described, clips, such as shown by Figure 6 of the drawings may be readily and easily formed from blanks comprising strips of metal, the clips when formed having extensions 45, that may be forced through a display card, and bent laterally, so 10 15 that articles such as tubes of solder, tooth paste, or the like may be readily secured on the display card.

Having thus described the invention, what is claimed is:

1. In a metallic clip forming machine, a frame, a table on the frame, an anvil on the table, said table having slots formed therein, angle bars secured to the table and arranged in parallel spaced relation with each other at opposite sides 25 of the slots, cover plates secured to the angle bars and providing guideways, one of the cover plates having a cut out portion providing an entrance to the space between the angle bars, whereby blanks to be formed into clips may be 30 inserted in the guideways at a point adjacent to the anvil, dies movable between the angle bars and having curved portions adapted to cooperate with the anvil in bending a blank, and means for operating the dies.

2. In a metallic clip forming machine, a frame, a table on the frame, said table having slots, angle bars secured to the table top adjacent to the slots, cover plates secured to the angle bars and providing guideways, an anvil supported by 40 one of the cover plates, one of the cover plates having a slot whereby blanks to be formed into clips may be positioned adjacent to the anvil, dies movable within the guideways adapted to engage a blank resting against the anvil whereby 45 the blank is bent into clip formation, and chutes secured under the table and adapted to receive the clips, after the clips have been formed by the dies.

CHARL SJÖGREN. 50
